STUDENT PILOT'S INSTRUCTION VISOR

Bertrand M. Cooper, Mission, Kans., and Amherst M. Parkison, Kansas City, and Gail A. Storck, Kansas City North, Mo., assignors to Trans World Airlines, Inc., Kansas City, Mo., a corporation of Delaware

Application October 18, 1952, Serial No. 21,894

Term of patent 14 years

(Cl. D57—1)

To all whom it may concern:

Be it known that we, Bertrand M. Cooper, a citizen of the United States, residing at Mission, Kansas, in the county of Johnson and State of Kansas, Amherst M. Parkison, a citizen of the United States, residing at Kansas City, Missouri, in the county of Jackson and State of Missouri, and Gail A. Storck, a citizen of the United States, residing at Kansas City North, Missouri, in the county of Clay and State of Missouri, have invented a new, original, and ornamental Design for a Student Pilot's Instruction Visor, of which the following is a specification, reference being given to the accompanying drawing, forming a part thereof.

Fig. 1 is a top plan view of student pilot's instruction visor, showing my new design.

Fig. 2 is a front elevational view thereof;

Fig. 3 is an elevational view of one side thereof; and

Fig. 4 is an elevational view of the opposite side thereof.

We claim:

The ornamental design for a student pilot's instruction visor, as shown.

BERTRAND M. COOPER.
AMHERST M. PARKISON.
GAIL A. STORCK.
